UNITED STATES PATENT OFFICE.

ISAAC M. SPENCER, OF OSCEOLA, ILLINOIS.

AX.

SPECIFICATION forming part of Letters Patent No. 463,002, dated November 10, 1891.

Application filed April 16, 1891. Serial No. 389,199. (No model.)

To all whom it may concern:

Be it known that I, ISAAC M. SPENCER, a citizen of the United States of America, residing at Osceola, in the county of Stark and State 5 of Illinois, have invented certain new and useful Improvements in Axes; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

This invention relates to improvements in 15 axes.

The object of the invention is to provide an ax with a bit on its upper edge as well as its front edge, so that there will be less friction in withdrawing the cutting-edge; and it consists in providing an ax with a bit on the upper portion of the head of the ax in front of 20 its eye, as will be hereinafter fully set forth, and particularly pointed out in the claim.

In the accompanying drawings, forming 25 part of this specification, Figure 1 is a side view of an ax constructed in accordance with my invention, and Fig. 2 a sectional view taken on the line $x-x$ of Fig. 1.

The head and eye of the ax are made in the 30 usual manner, and the front edge is provided with a bit B, which forms the usual cutting-edge. The upper edge of the ax in front of the eye is extended, as shown, and provided with a bit or sharp edge C. These bits B and 35 C meet to provide a sharp corner. An ax

thus constructed can be easily withdrawn from the wood in chopping, and wood-cutting is therefore rendered much easier. The construction is also advantageous in dressing lumber or logs, as the upper bit can be used 40 in dressing or cutting off small slivers much more expeditiously than with axes as usually made. The bit C can also be used for cutting overhead in clearing branches and for other purposes. 45

This invention may also be applied to double-bitted axes.

I am aware that prior to my invention it has been proposed to provide an ax with a concave cutting-edge, which has been extended around, so that the front portion of the head at its upper and lower edges would have a cutting-edge, thus making an ax which could be reversed upon the handle, and I do not claim such construction as my invention; but 50 55

What I do claim as new, and desire to secure by Letters Patent, is—

As an improved article of manufacture, an ax-head having a poll and eye of ordinary construction, and a bit C, formed on the upper portion of the head forward of the eye to extend above the same and joining at the front with a bit B, substantially as shown, and for the purpose set forth. 60

In testimony whereof I affix my signature in 65 presence of two witnesses.

ISAAC M. SPENCER.
